CLEANING AND WASHING MACHINE

Ivanhoe Peter Denyssen, Yeadon, and Richard W. Stanley, Drexel Hill, Pa., assignors to American Viscose Corporation, Wilmington, Del., a corporation of Delaware

Application June 6, 1942, Serial No. 446,016

16 Claims. (CL. 134—152)

1

This invention relates to a machine for cleaning and washing objects, particularly adapted for operation upon such objects as the spinnerets which are employed in the manufacture of artificial filaments. While the description herein-after will refer specifically to operation upon spinnerets, it is to be understood that the machine is also applicable to the washing and cleaning of other objects particularly those which have indentations or perforations of relatively small dimensions requiring cleaning.

It is an object to provide a device which is capable of applying a cleaning fluid in an efficient manner to thoroughly clear the perforations of the spinnerets or the surfaces, perforations and other portions of the objects desired to be cleaned. Another object is to efficiently clean a plurality of faces of such objects during a single operation. A further object is to clean a plurality of faces of such objects during a single operation and, in the case of perforated objects, such as spinnerets, to alternately apply the cleaning fluid to the perforations from opposite sides of the objects. A further object is to provide a device for automatically moving the spinnerets and the means for applying the cleaning fluid relative to one another in a predetermined manner to effect complete traversal by the fluid applying means of all the surfaces to be cleaned. Another object is to provide for automatically stopping the cleaning operation upon completion of the cleaning of each charge. Other objects of the invention will be apparent from the drawing and the description thereof hereinafter.

In the drawing, illustrative of the invention,

Figure 1 is, with the exception of a few parts which will be apparent from the description herein-after, a transverse cross-section taken on line I—I of Figure 2.

Figure 2 is a longitudinal vertical cross-section taken on line II—II of Figure 1.

Figure 3 is a cross-sectional view taken on line III—III of Figure 2.

Figure 4 is a cross-sectional view taken on line IV—IV of Figure 2.

Figure 5 is a developed elevation of a modified form of cylindrical cam.

Figure 6 is a diagrammatic showing of the relative path of one of the cleaning nozzles with respect to the spinneret facing it obtained by the use of the device of Figure 1.

Figure 7 is a cross-sectional view taken on the line VII—VII of Figure 1.

Figure 8 is a detail view showing a cleaning nozzle in cross-section.

2

Figure 9 is a cross-sectional view of one form of object-holder, and

Figure 10 shows diagrammatically a circuit for automatically stopping the device.

5 In general, the machine comprises a base 2 for supporting the driving mechanism 3 and an upright cylinder 4 within which a tubular member 5 is supported for vertical reciprocation. A head 6 which carries the object holder 7, is mounted for oscillatory motion with respect to the tubular member 5 and is connected by means of a flexible diaphragm 8 to the top of a casing 9 which is mounted upon the base 2 and houses the driving mechanism 3 of the device. A hood 10 of suitable shape is mounted above the casing 9 and is provided with a plurality of spray nozzles 11 for applying a cleaning fluid to the objects which are moved in a manner hereinafter described within the hood. The head 6 and flexible diaphragm 8 serve as a septum to prevent any of the fluid used for cleaning from entering the casing 9 within which the operating mechanism 3 is housed. A suitable drain connection 12 may be provided at the base of the hood and a cover 13 may be provided in the top of the hood 10 to permit ready insertion of and removal of the objects to be cleaned.

The holder 7 of the objects to be cleaned is more particularly shown in Figure 9 and comprises two 30 parallel plates 14 provided with apertures 15 adapted to receive a cylindrical spinneret 16 whose flanges 17 are held between the two plates. The apertures 15 in the two plates are substantially of the same size and substantially in register. The two plates 14 charged with the spinnerets 16 are adapted to slide within the grooved ways 18 (see Figure 2) provided in the upright sides and, if desired, in the base 7 of the U-shaped holder. The plates may be adapted to receive any number of vertical rows of spinnerets, six being shown in Figure 2. Different plates may be provided to receive spinnerets of different sizes and when smaller spinnerets are being treated, a greater number of spinnerets may be placed in a vertical row within any given machine having a given size of U-shaped holder.

As appears from Figure 1, two rows of spray nozzles 11 are disposed in the hood 10 to one side of the holder 7 and a third row vertically offset 50 from the other two is disposed in the hood on the other side of the holder. Each of the three rows preferably has as many spray nozzles 11 as there are vertical rows of spinnerets in the holder and these nozzles are disposed so that one in each row faces one of the vertical rows of spin-

nerets. Any form of spray means may be employed. It is preferred, however, that a relatively fine sharp jet of the fluid be employed when objects which have perforations of relatively small diameter require cleaning. Figure 8 shows a common form of nozzle adapted to provide such a fine jet of fluid. The particular nozzle shown has the further advantage of being self-cleaning, being provided with a fixed pin 20 against which the nozzle sleeve 21 is forced by spring 22 when the cleaning fluid is periodically shut off at the termination of each operating cycle. The pin is tapered to a point so that its end enters the orifice of the nozzle and forces any foreign particles out when the cleaning fluid is shut off.

The driving mechanism 3 for effecting the relative motion between the spinnerets 17 and the spray nozzles 11 comprises two functional systems which are interconnected with each other. Both of these systems operate simultaneously to impart a compound motion to the spinneret holder 7. This compound motion is made up of a vertical component and a horizontal component. The horizontal component is essentially an oscillatory motion imparted to the head 6 upon which the holder 7 is mounted and the vertical component may be continuous or more or less intermittent vertical rise of the head 6 which is imparted by means of the tubular member 5.

The system for imparting the horizontal component of the motion of the head 6 and holder 7 may be understood by referring to Figures 1, 2, and 7. The tubular member 5 has mounted for rotation therein two cylindrical members 23 and 24 each of which is attached to a short vertical sleeve 25 by means of the ribs 26. Two pins 27 mounted for rotation within the sleeves 25 act as the sole supporting connection of the head 6 to the tubular member 5. The base of the cylindrical member 24 is provided with internal longitudinal grooves 28 (see Figure 7) adapted to cooperate with the splined shaft 29 rotatably mounted in a suitable bearing in the base of the machine. Oscillation of this splined shaft 29 is accomplished by lever 30 and link 31 the former of which is keyed or otherwise secured to rotate with the splined shaft and the latter is provided with a bored end 32 for embracing an eccentric 33 on the plate 34 rotated by a shaft 35 within the base of the machine. This shaft 35 is connected to be driven by the motor 36 through a series of gears 37 and 38, 39 and 40, 41 and 42, and 43 and 44. A mechanism comprising a slide block 45 and grooved plate 46 is interposed between gears 42 and 43. Figure 3 is a view looking down upon this portion of the mechanism. The slide block 45 is rotatably mounted eccentrically on gear 42 and slides within the groove 47 in the more or less diamond-shaped plate 46 which is mounted for rotation with the lower gear 43. The axis of gear 43 is offset from that of gear 42 a distance which is different than the distance between the block 45 and the axis of the upper gear 42. The purpose of this mechanism is to convert what would ordinarily be a simple harmonic motion to a motion of the eccentric 33 which imparts a more nearly constant speed of oscillation of the holder 7 for the spinnerets. If desired, this slide block and grooved plate connection may be omitted and replaced by a suitable gear connection but it is preferred to employ this mechanism in order to obtain the most efficient use of the cleaning fluid.

In order to impart a vertical component to the

motion of the spinneret holder 7, tubular member 5 is provided with a transverse cross-pin 48, the ends of which project beyond the exterior cylindrical surface of the member. The stationary cylinder 4 is provided with a pair of opposite vertical slots 49 through which the pin 48 is adapted to extend and a cylindrical cam plate 50 is secured to a cylindrical member 51 which is mounted for rotation within a suitable circular guideway 52 within the base of the machine. The cam 50 has its upper edge cut to form an incline upon which one end of the pin 48 rides. The rotatable cylinder 51 upon which the cam plate is mounted is provided with an internal gear 53 which meshes with a gear 54 keyed to a shaft 55 mounted within the base of the machine. This shaft 55 is driven intermittently through the following connections. Mounted on the shaft 35 for rotation therewith is the driving wheel 56 of a Geneva type of intermittent mechanism (more particularly shown in Figures 3 and 4) which driving wheel is provided with pins 57 for intermittently entering the radial slots 58 of the star wheel 59 mounted for rotation with the shaft 60 carrying the pinion 61 which meshes with the gear 62 for driving the shaft 55 and the gear 54 which ultimately drives the cylindrical cam plate 50 through its internal gear 53. The shaft 60 carrying the star wheel 59 extends internally of 30 and freely rotates with respect to the shaft carrying gear 43 and grooved plate 46. The ratios of the various gears are such that the intermittent mechanism rotates the cylindrical cam 50 through a fraction of a revolution in a direction such that the cam elevates the tubular member 5 and the spinneret holder 7 at the end of each oscillatory stroke of that holder. The amount of the rise is also predetermined to cause the area of the spinneret which is directly sprayed by the 40 jet to slightly overlap that sprayed in the immediately previous oscillatory stroke. The path of the spray relative to a spinneret 16 is indicated by the dotted line of Figure 6.

The base 2 of the machine may be provided 45 with an oil pan 63 and a dash pot 64 adapted to cooperate with a plunger 65 fastened to the bottom of the vertically reciprocable tubular member 5 to cushion its fall which occurs preferably at the beginning of operation of the machine as will be described hereinafter. The dash pot 64 is provided with a constricted opening 66 to the oil pan 63 and a communicating channel 67 to an oil line 68 so that upon each fall of the reciprocable tubular member 5, oil is pumped to the bearing surfaces within which the reciprocable member 5 operates and from there through the conduit 69 to the top of the gear trains of the driving mechanism.

The cylindrical cam plate 50 may be provided 60 with a projecting finger 70 in vertical alignment with the highest portion of the cam surface. A limiting switch 71 having contact members 72 and 73 is provided adjacent the cylindrical cam 50. Contact 73 is fixed while a spring metal arm 74 supports contact 72 so that it is normally biased into contact with 73 but is adapted to be separated therefrom when a projection 75 of insulating material is brought into contact with the projection 70 on the cam plate 50 in the manner shown 65 in Figure 2. The switch 71 is arranged so that the contact members 72 and 73 are in approximate vertical alignment with the transverse pin 48 so that its opening occurs when the pin 48 is at the highest point of the cam surface 50. This 70 limiting switch 71 may be connected by any suit-

able circuit to effect stopping of the motor 36. One form of circuit is shown in Figure 10 where two coils 76 and 77 are shown in series with the switch contacts 72 and 73. The coil 76 when energized is adapted to act upon a core 78 to close the switch blades 79 to connect the motor to the line (3 phase being shown). The coil 77 when energized opens the valve 80 in the fluid supply line through the core 81. Springs 82 and 83 normally oppose the action of the coils 76 and 77 respectively and upon de-energization of the coils, these springs open switch blades 79 and close the valve 80. A stop switch 84 which is normally held closed by a spring may be provided for making emergency stops. There is also provided a starting switch 85 which is shunted across the contacts 72 and 73. This switch 85 is normally held open by a spring.

As will appear from the description hereinabove, the holder 7 is in its uppermost position at the time of loading, which is the position shown in Figures 1 and 2. Thereupon the starting switch 85 is manually closed until the projection 70 on the cylindrical cam plate 50 separates from projection 75 to permit closing of the contacts 72 and 73 of the limiting switch 71. The sprays and the motor 36 start immediately upon the closing of the switch 85 and the tubular member 5 with the spinneret holder 7 falls to its lowermost position, the dash pot 64 cushioning such fall, and the holder 7 is oscillated back and forth, such oscillation being accompanied with an intermittent vertical motion at the end of each oscillatory stroke so that the topmost horizontal row of spinnerets 16 in the holder 7 are subjected to the sprays of the lowermost row of nozzles 11, then to the sprays from the nozzles 11 on the other side of the spinneret holder 7, and finally to the top row of nozzles 11. The arrangement is such that the portions of the spinnerets 16 which have just been cleaned continuously move up into the region above the sprays 11 where they are neither affected by the sprays or by drippings therefrom.

Figure 5 shows a developed view in elevation of a modified form of cylindrical cam plate 50. As compared to that of Figures 1 and 2 which has a cam surface of constant slope except at the position of vertical drop, that of Figure 5 has a number of equally spaced sharp rises 86 which alternate with the more gently sloped portions 87 of the cam surface which extend through a greater fraction of the periphery of the cam plate 50. In this embodiment, each gently sloped portion 87 effects an elevation of the spinneret holder 7 a distance equal to the diameter of a spinneret 16 which elevation may be performed by about 8 to 20 strokes of the intermittent mechanism and each short and more steeply sloped portion 86 of the cam surface causes the elevation of the spinneret holder 7 a distance equal to the vertical distance between the spinnerets in adjacent horizontal rows and this elevation is preferably effected in a single stroke of the intermittent mechanism. When this type of cam plate is employed, the vertical distance between the center lines of adjacent rows of spray nozzles 11 preferably equals the vertical distance between the centers of the spinnerets 16. In order to cover the entire surface of all of the spinnerets in a given vertical row with all three of the spray nozzles 11 facing the vertical row when employing this arrangement, it is necessary to have two more of each of the gentle and steep steps 86 and 87 in the cam plate than the number of spinnerets 75

16 in the vertical row in the holder 7 and Figure 5 represents a form of cam cylinder 50 which may be employed with a spinneret holder 7, such as that of Figure 9, which retains 8 horizontal rows of spinnerets 16.

The machine may employ any cleaning fluid, such as water, organic solvents, whether cold or heated, steam, air blasts, and, if desired, the fluid stream may contain small particles of abrasive 10 to exert a polishing action upon the objects being treated. Normally, in the application to spinnerets, it is preferred to use a form of organic solvent capable of dissolving rapidly the particular material with which the spinneret perforation 15 may be clogged or contaminated.

While it is preferred to employ a plurality of rows of spray nozzles as shown in Figures 1 and 2, it is nevertheless within the contemplation of the invention to omit one, or all except one, horizontal 20 row of such nozzles, particularly where it is not desired to clean both surfaces of an object.

While preferred embodiments of the invention have been shown, it is to be understood that changes and variations may be made without departing from the spirit and scope of the invention 25 as defined by the appended claims.

We claim:

1. In apparatus for cleaning objects, means for holding the object to be cleaned, means for spraying a cleaning fluid against said object, means for oscillating, at substantially uniform linear speed, the object back and forth past the spray means, and means for intermittently moving the object past the spray means in a direction transverse to the direction of oscillation.

2. In apparatus for cleaning objects, means for holding the object to be cleaned, means for spraying a cleaning fluid against said object, means for oscillating the object back and forth past the spray means, and means for intermittently moving the object past the spray means in a direction substantially at right angles to the direction of oscillation approximately at the end of each oscillatory stroke.

3. In apparatus for cleaning objects, a carrier for holding a plurality of objects to be cleaned in a plurality of rows, at least one row of means for spraying a cleaning fluid against said objects, means for oscillating the objects back and forth in a direction parallel to that of the row of spray means and means for moving the object past the spraying means in a direction transverse to the direction of oscillation intermittently at approximately the end of each oscillatory stroke.

4. In apparatus for cleaning objects, a carrier for holding a plurality of objects to be cleaned in a plurality of rows, at least one row of means for spraying a cleaning fluid against said objects, means for oscillating the carrier and thereby the objects back and forth past the spray means, means for moving the carrier in a direction transverse to the direction of oscillation intermittently at approximately the end of each oscillatory stroke a fraction of the distance across said objects and means for moving the carrier to bring the next row of objects in the carrier in a single stroke into opposition to the spray means upon completion of each row of objects.

5. In apparatus for cleaning objects, means for holding the object to be cleaned, means for spraying a cleaning fluid against said object from a plurality of sides of said object, means for oscillating the object back and forth past the spray means, and means for moving the object past the spray means in a direction transverse to the

direction of oscillation intermittently at approximately the end of each oscillatory stroke.

6. In apparatus for cleaning perforated objects, means for holding the objects to be cleaned, means for spraying a cleaning fluid against said object in succession from opposite sides of said object in the approximate direction of the perforations, means for oscillating the object back and forth past the spray means, means for moving the object past the spray means in a direction transverse to the direction of oscillation intermittently at approximately the end of each oscillatory stroke, the spray means on one side of the object-holding means being offset from the spray means on the other side in the direction of one component of the relative motion.

7. In apparatus for cleaning perforated objects, a carrier for holding a plurality of objects to be cleaned in a plurality of rows, a plurality of rows of means for spraying a cleaning fluid against said objects in succession from opposite sides of said object, means for oscillating the carrier so that the object oscillates back and forth past the spray means adjacent them, means for moving the carrier with the object past the spray means in a direction transverse to the direction of oscillation intermittently at approximately the end of each oscillatory stroke, said rows of spray means being offset in the direction of intermittent motion a distance approximately equal to the center to center distance of the corresponding rows of objects in the carrier.

8. In apparatus for cleaning objects, means for spraying a fluid, a carrier for said objects, a slidable member, means on said slidable member mounted pivotally on an axis substantially parallel to the direction of sliding for supporting said carrier, means for oscillating said carrier supporting means about its axis, and means for sliding said slidable member.

9. In apparatus for cleaning objects, means for spraying a fluid, a carrier for said objects, a vertically movable member, means on said member mounted pivotally on a substantially vertical axis for supporting said carrier, means for oscillating said carrier supporting means about its axis, and means for intermittently elevating said member substantially at the end of each oscillatory stroke of said carrier supporting means.

10. In apparatus for cleaning objects, at least one row of means for spraying cleaning fluid, a carrier for the objects, a member slidable in a direction transverse of the spray means row, at least two members on said slidable member mounted pivotally on substantially parallel axes lying substantially in a plane substantially parallel to the direction of motion of the slidable member and to the spray means row, said carrier being pivotally connected to each of said pivotal members to form the fourth side of a parallelogram linkage, means for oscillating said parallelogram linkage, means for sliding said slidale member a step at a time approximately at the end of each oscillatory stroke of said parallelogram linkage.

11. In apparatus for cleaning objects, at least one row of means for spraying cleaning fluid extending substantially horizontally, a carrier for the objects, a substantially vertically movable member, at least two members on said movable member mounted pivotally on substantially vertical axes, said carrier being pivotally connected to each of said pivotal members to form the fourth side of a parallelogram linkage, means for oscillating said parallelogram linkage, a cylin-

drical cam having a sloped surface, a pin secured to said vertically movable member arranged to ride upon said sloped surface, and means for effecting a partial rotation of said cam intermittently approximately at the end of each oscillatory stroke of said parallelogram linkage.

12. In apparatus for cleaning objects, at least one row of means for spraying cleaning fluid extending in a horizontal direction, a carrier for the objects, a vertically movable tubular member, at least two members mounted pivotally on substantially vertical axes within the tubular member, said carrier being pivotally connected to each of the pivotal members to form the fourth side of a parallelogram linkage, one of said pivotal members being provided with an internal sleeve having substantially vertical grooves, a splined shaft vertically slidable in said grooved pivotal member, means for oscillating said splined shaft, a cylindrical cam having a sloped surface, a pin secured to said tubular member extending transversely therefrom and arranged to ride upon said sloped surface, and means for effecting a partial rotation of said cam intermittently approximately at the end of each oscillatory stroke of said parallelogram linkage.

13. In apparatus for cleaning objects, a casing, a hood mounted over an opening in said casing, means for spraying a cleaning fluid mounted on said hood, a carrier for supporting the objects in said hood, a flexible diaphragm secured to said carrier below the carrier and secured to the juncture between the hood and casing to seal the communicating opening between the casing and the hood, operating mechanism in said casing comprising means for oscillating said carrier in one direction, and means for intermittently moving said carrier in a direction transverse to that of oscillation substantially at the end of each oscillatory stroke.

14. In apparatus for cleaning perforated objects, means for holding the object to be cleaned, means for spraying a cleaning fluid against said object in succession from opposite sides of said object in the approximate direction of the perforations therein, means for imparting relative reciprocatory motion between the object and spray means, said motion being substantially parallel to a plane substantially perpendicular to the direction of the perforations, and means for imparting relative motion between the object and spray means in a direction transverse of that of the first mentioned relative motion and substantially perpendicular to the direction of the perforations thereby to relatively traverse the spray means through a path succeeding generally parallel portions of which are disposed in opposition to adjacent strips of the object surface.

15. In apparatus for cleaning perforated objects, means for holding the object to be cleaned, means for spraying a cleaning fluid against said object in succession from opposite sides of said object in the approximate direction of the perforations therein, means for imparting relative reciprocatory motion between the object and spray means, said motion being substantially parallel to a plane substantially perpendicular to the direction of the perforations, and means for imparting relative motion between the object and spray means in a direction transversely of that of the first mentioned relative motion and substantially perpendicular to the direction of the perforations thereby to relatively traverse the spray means through a path succeeding generally parallel portions of which are disposed in oppo-

sition to adjacent strips of the object surface, the spray means on one side of the object-holding means being offset from the spray means on the other side in the direction of one of said relative motions.

16. In apparatus for cleaning objects, means for holding the object to be cleaned, means for spraying a cleaning fluid against said object, means for reciprocating the object back and forth past the spray means, and means for intermittently moving the object past the spray means in a direction transverse to the direction of reciprocation.
